UNITED STATES PATENT OFFICE.

CHARLES MANDELL BRENNER, OF SHREVEPORT, LOUISIANA.

ICE-CREAM CONTAINER.

Application filed September 7, 1926. Serial No. 134,102.

This invention relates to an improved container for ice cream, and the object of the invention is to provide a container which eliminates the necessity for washing the cans while rendering the handling of the cream in a far more sanitary manner than is now the practice.

Another object of the invention resides in the provision of an ice cream container which maintains the ice cream frozen and yet entirely isolates the ice and salt from the ice cream and from the opening through which access is had to the ice cream.

A still further object resides in the provision of a container having these advantages and capacities and which is of simple and durable construction, practically indestructible and easy and comparatively inexpensive to manufacture and handle.

Other objects and advantages reside in certain novel features of the construction, arrangement and combination of parts which will be hereinafter more fully described and particularly pointed out in the appended claim, reference being had to the accompanying drawings forming a part of this specification, and in which:—

Figure 1 is a view in elevation showing one embodiment of the invention,

Figure 2 is a view thereof in diametrical vertical section, parts being shown in elevation for the sake of illustration,

Figure 3 is a sectional view on the line 3—3 of Figure 2,

Figure 4 is a fragmentary sectional view showing a modified form of closure for the ice cream container, and

Figure 5 is a bottom plan view of the parts shown in Figure 4.

Referring to the drawings, the numeral 1 designates an outer or ice container which is made of metal adapted to resist the corroding effect of salt and ice. The container 1 has a tubular body portion 2 and a bottom 3 and in the bottom 3 an opening 4 is provided to permit of the ice and salt or other refrigerant being placed within the container 1. Around the opening 4 a flange 5 is provided and against this flange 5 a closure plate 6 seats, the closure plate 6 being held in position by a crab or spider 7 with which a stud bolt 8 coacts, the stud bolt passing through an opening in the closure plate and having threaded connection with the hub of the spider or crab. In lieu of this form of closure

the flange around the opening 4 may be offset inwardly to a greater extent, as indicated at 5^a, in Figure 4, and against the outer face of the lip 5^b of this flange a closure plate 6^a may be seated. The closure plate 6^a is formed against the lip 5^b by means of a screw 8^a bearing against the plate 6^a and threadedly connected with the hub of a spider 7^a, the spider 7^a being mounted on segmental guides 10 of Z form in cross section. At the upper end of the tubular body 2 an annular head plate 15 is provided and may be integral with or otherwise suitably connected to the body 2. An inner or ice cream container 16 is provided and comprises a tubular body 17 having a closed bottom 18 and having a flange 19 at its upper end whereby it is connected with the annular head plate 15. The flange 19 may be welded or otherwise suitably secured to the head plate and to the tubular body 17 of the container 16 and as far as practical and desirable these several parts may be integral with each other. Within the container 16 a package of ice cream is placed, the package of ice cream being contained in a paper carton 20 and being entirely housed and contained in the inner container 16. The paper carton which contains the body of the ice cream may be waxed or paraffined and is sealed at the factory where the ice is made. In other words at the factory the ice cream is poured into the cartons, sealed and frozen therein. Thereafter the cartons with the ice cream in the same are placed in the inner container 16 and the inner containers are kept sealed and cool by the ice in the outer containers. The inner containers 16 are made of metal having a relatively high degree of conductivity so that the ice within the outer container will maintain the ice cream in a frozen condition. On top of the carton of ice cream and in the recess provided by the flange 19 a closure plate 25 is seated. This closure plate is held in position by a clamping bolt 26 which has a foot piece 27 bearing down on the plate 25. The upper end of the clamping screw 26 is threadedly connected with a cap or cover 28 which is releasably fastened to the upper end of the annular head plate 15 of the outer container. Any suitable means may be employed for fastening the cap 28 to the head plate 15 and one such means consists of segmental projections 30 integral with the flange of the cap 28 and co-operable with segmental guides 31 of Z-shape form in cross sec-

tion, the guides 31 being secured by bolts and nuts 32 to the head plate 15.

By entirely isolating the ice or refrigerant from the entrance to the ice cream container 5 the possibility of ice or salt getting into the ice cream is obviated and the operation of removing the ice cream is greatly facilitated since no ice need be removed when the ice cream is being removed. The feature of providing the ice cream in cartons avoids the necessity of washing out the containers 10 since the ice cream does not directly touch the same. The metal making up the containers is practically indestructible and will not 15 rot in a short time as will the wooden tubs now in use.

It is to be understood that the means for closing the bottom of the outer container and the means for closing the top of the inner container may be varied without departing from the spirit of the invention. Of course, it may 20 also be desirable to use heat insulation or a casing of heat insulating material for the outer material. Such a feature is one well

known in the art and needs no further explanation. 25

I claim:—

A device of the character described, comprising an outer container having an annular head plate, an inner container made integral 30 with the head plate of said outer container and depending into said outer container, said inner container having a lateral flange offset downwardly from the head of the outer container and forming a seat at the upper end of the inner container, an inverted cup-shaped closure having a lateral flange detachably mounted on the head of the outer container and arranged over said inner container, a closure plate to seat on the flange of the inner 35 container, a clamping bolt adjustable in said cup-shaped closure and having a foot to bear on said plate and hold it in operative position, said outer container having an opening for the insertion of a refrigerant and said opening being equipped with an air tight closure. 40 45
